Primary Examiner — Ricky Pham(74) *Attorney, Agent, or Firm* — Stetina Brunda Garred & Brucker(57) **CLAIM**

The ornamental design for a water bottle diffuser tool, as shown and described.

DESCRIPTION

FIG. 1 is a perspective, exploded view of the water bottle diffuser tool, showing my new design;

FIG. 2 is a front, exploded view of the water bottle diffuser tool shown in FIG. 1;

FIG. 3 is a right side, exploded view of the water bottle diffuser tool shown in FIG. 1;

FIG. 4 is a rear, exploded view of the water bottle diffuser tool shown in FIG. 1;

FIG. 5 is a left side, exploded view of the water bottle diffuser tool shown in FIG. 1;

FIG. 6 is a top view of the water bottle diffuser tool shown in FIG. 1;

FIG. 7 is a bottom view of the water bottle diffuser tool shown in FIG. 1;

FIG. 8 is a perspective, assembled view of the water bottle diffuser tool shown in FIG. 1;

FIG. 9 is a front, assembled view of the water bottle diffuser tool shown in FIG. 1;

FIG. 10 is a right side, assembled view of the water bottle diffuser tool shown in FIG. 1;

FIG. 11 is a rear, assembled view of the water bottle diffuser tool shown in FIG. 1; and,

FIG. 12 is a left side, assembled view of the water bottle diffuser tool shown in FIG. 1.
